UNITED STATES PATENT OFFICE.

EMIL RUMSCH, OF FORST-LAUSITZ, GERMANY.

MANGLE WITH VARIABLE-PRESSURE ROLLERS.

Application filed April 26, 1927, Serial No. 186,769, and in Germany July 1, 1926.

Mangles with a central steam heated cylinder and pressure rollers placed around the cylinder with means for varying the pressure of the said rollers, are of high efficiency.

- 5 The pressure rollers however are usually covered with textile material blankets and as a result there occurs wet steam in the covering in the course of a short time which is a hindrance and also renders it necessary to replace the roller coverings frequently, with interruptions to the working of the apparatus and, of course, increased working costs.

The present invention has for object a mangle having pressure rollers arranged as above set forth, that is with means for varying the pressure, in which apparatus the inconvenient and annoying wet steam may be removed as formed and according to the invention each pressure roller interior is put into communication with a suction device which will exert a suction effect on the interior of the roller whilst still allowing of variation of the pressure, that is, variation in the position of a pressure roller relative to the central cylinder, as desired.

The invention in a very convenient method of carrying it into effect will now be fully described with reference to the annexed drawings wherein Figure 1 is an end elevation of 30 a mangle with five pressure rollers and Figure 2 is a fragmentary view taken at right angles to Figure 1 and showing to an enlarged scale the ends of a pressure roller and the end of the central cylinder with the means for allowing of variation of roller pressure whilst still maintaining the said roller in tight contact with a suction device.

The pressure rollers *a* are perforated and covered with blankets of textile material and 40 they are borne in curved end brackets *d* in the usual manner, the brackets being pivoted so that the rollers may be raised from the central heated cylinder *c*. Each pressure roller is provided at one end with the conical end *b* and the roller is maintained against the central cylinder by springs contained in a spring casing *e*.

Upon one end bracket *d* is placed a casing and through a pipe *b'* passing through the 50 end *b* and roller bearing *h* the roller is in

communication with the interior of the said casing *f* the latter being slotted for the purpose. The slot is of a length sufficient to allow of movement under the spring pressure, of the pressure roller to which *b* and *b'* are attached. On the casing *f* is the pipe block *g* for the placing in position of a suction pipe *g'*.

Each pressure roller is borne in the bracket *d* by means of a bearing *h* already referred to, and in order to prevent access of air to the casing *f* each such bearing on the suction side is provided with a flange *i* and a felt or like washer *k* having an oval central orifice, the said washer being pressed against the face of the casing *f* by the flange *i*. The flange and washer are sufficiently long to ensure that the movement of the pressure roller as a result of variation of spring pressure will not cause the slit in the bracket *d*, through which the pipe *b'* enters, to be uncovered, and in all positions the partial vacuum caused by suction will maintain the washer *k* against the casing *f*, whilst the washer offers no hindrance to movement of the roller bearing.

It will be understood that variations of the mechanical details may be introduced so long as the spirit of the invention, viz: arrangement of a suction device which will cause a partial vacuum in each textile material covered pressure roller whilst still permitting the said roller to have variable pressure applied between it and the central cylinder, is preserved.

I claim:

1. In a mangle, a central cylinder, a plurality of textile blanketed pressure rollers placed around the cylinder on brackets, movable bearings for the said rollers in the said brackets, with means for applying variable pressure to the said roller bearings, an exhaust casing in communication with the interiors of the pressure rollers, and air-tight packings between the bearings and the exhaust casing, and preserving their air tightness in all positions of the movable bearings.

2. In a mangle, a central cylinder, a plurality of pressure rollers placed around the said cylinder on brackets, a conical end on

each pressure roller and a bearing within a bracket for such conical end, an exhaust casing on one of the brackets, a communication pipe between the interior of each pressure roller and the said exhaust casing which pipe passes through the conical end, a slot in the bracket through which slot the said pipe

passes, such slot allowing of movement of the said pipe, a flange on the pressure roller bearing, and a flexible washer between the flange and the exhaust casing. 10

In testimony whereof, I have hereunto set my hand.

EMIL RUMSCH.
